United States Patent Office

Des. 219,344
Patented Dec. 1, 1970

219,344

ENCAPSULATED VACUUM SWITCH

Thomas E. Curtis, Centralia, Mo., assignor to A. B. Chance Company, Centralia, Mo., a corporation of Missouri

Filed May 12, 1969, Ser. No. 17,124

Term of patent 14 years

Int. Cl. D13—03

U.S. Cl. D26—13

Fig. 1.

Fig. 2.

Fig. 4.

FIG. 1 is a perspective view of an encapsulated vacuum switch, showing my new design;

FIG. 2 is a side elevational view thereof;

FIG. 3 is an elevational view of one end thereof;

FIG. 4 is an elevational view of the opposite end thereof;

FIG. 5 is a perspective view of a modified form showing my new design;

FIG. 6 is an elevational view of one end of the encapsulated vacuum switch as shown in FIG. 5; and

FIG. 7 is a reduced scale bottom view thereof, the bottom of both forms claimed being the similar.

I claim:

The ornamental design for an encapsulated vacuum switch, as shown and described.
